The ornamental design for a gate, as shown and described.

DESCRIPTION

FIG. 1 is a top and front perspective view of a gate showing a new design;

FIG. 2 is a front view thereof with the back view being a mirror image thereof;

FIG. 3 is a left side view thereof with the right side being a mirror image thereof;

FIG. 4 is a top view thereof; and,

FIG. 5 is a bottom side view thereof.

The dashed lines of FIG. 5 show environmental conditions only and form no part of the claimed design.
